UNITED STATES PATENT OFFICE.

FRED A. REARDON, OF HAVERHILL, MASSACHUSETTS, ASSIGNOR TO HAMEL SHOE MACHINERY COMPANY, OF BRIDGEPORT, CONNECTICUT, A CORPORATION OF MASSACHUSETTS.

WOOD-HEEL-ATTACHING JACK.

1,366,935.

Specification of Letters Patent.

Patented Feb. 1, 1921.

Application filed June 6, 1917. Serial No. 173,134.

To all whom it may concern:

Be it known that I, FRED A. REARDON, a citizen of the United States, and a resident of Haverhill, county of Essex, and State of Massachusetts, have invented an Improvement in Wood-Heel-Attaching Jacks, of which the following is a specification.

In attaching wood heels to shoes by the usual hand-nailing process, which, so far as I am aware, is the only process, at present, in practical use, it is customary to apply glue to the heel or heel seat and then to clamp the heel onto the seat in position and hold it thus clamped until the glue sets, after which the clamp is removed and the attaching nails are driven by hand from inside the shoe, the glue being relied on to hold the heel in place while this operation is performed.

This method is objectionable for several reasons some of the more important of which are as follows:—A considerable number of clamps must be provided, so that the workman may be continuously employed, this involving the provision of space and apparatus; further, the glue sometimes fails to hold the heel in position until the heel is securely attached, and moreover it requires considerable skill on the part of the wood-heel-nailer to perform the nail-driving operation rapidly and satisfactorily, the nails being frequently improperly placed and driven.

The object of my invention is to provide a means whereby the use of a plurality of clamps for each workman may be avoided, and the attaching nails driven easily and accurately by comparatively unskilled labor.

I accomplish this object by providing a form of clamp with which the heel may be firmly pressed against the heel seat of the shoe under practically all conditions, and the attaching nails may be driven while the heel is thus held thereby, and by providing, in connection therewith, nail-guiding means for causing the nails to be accurately directed as they are driven.

In the accompanying drawing in which an embodiment of my invention is shown:

Figure 1 is a side elevation of such a device.

Fig. 2 is a plan view thereof.

Fig. 3 is a longitudinal sectional view, on

an enlarged scale, illustrating the manner of driving the nails.

Fig. 4 is a detail plan view of the heel-part last support and

Figs. 5 and 6 are detail views of the opposite sides of the iron last.

According to my invention I provide a base 1, which is adapted to be rigidly secured to a bench, or other support, and a supporting bracket 2, comprising a pair of arms mounted on the end of a shaft 3, and extending oppositely with relation thereto, said shaft being rotatably mounted in a horizontal position in said base. Locking means are provided for holding said bracket 2 with its arms disposed in a vertical plane, comprising a bolt 4, mounted to slide in lugs 5, on the base and arranged to enter either of diametrically opposite recesses 6 in the hub 7 of the bracket 2. A spring 8 is arranged on the bolt 4, between one of the lugs 5 and a collar 9 on the bolt, to press the bolt into either of said recesses 6, and a finger 10 is provided on said bolt to afford a convenient means to withdraw the bolt and unlock the bracket, so that it may be rotated from one locked position to the other.

A clamp frame, 11 of approximately C-form, is provided, from the back of which two lugs 12 are arranged to project, the opposite sides thereof being suitably faced and arranged to fit between corresponding faces, on the adjacent sides of the arms of bracket, 2, and said lugs being mounted on a pivot shaft 13, which is mounted at its ends in the arms of said bracket, so that said frame 11 may swing back and forth through an arc somewhat greater than a semi-circle. The arms 11^a and 11^b of said frame 11 extend transversely of their pivotal support and, at their end-portions, are extended toward each other, so that their ends lie in a line which is approximately, though not necessarily, exactly, parallel to the pivot shaft 13. A heel-top engaging member, or block, 14 is connected by a pivot 15 to the end of the arm 11^a, said pivot being arranged at right angles to the plane of the frame 11, so that said block may swing to a limited extent in said plane, the block having a face formed thereon at the opposite side thereof from its pivot, adapted to

receive the top of an ordinary wood heel, a retaining lug 16 being formed at one side of said face.

- A screw threaded post, or rod 17 is 5 threaded in the other arm 11^b in a position approximately perpendicular to the face of block 14, so that it may be adjusted to and from the same, said post having a ball 18 on that end adjacent the block 14 and a handle 10 19 at its opposite end. An inside mailing heel-part last is connected to the ball-carrying end of said post 17 by a universal joint, as hereafter described, said last comprising a die-block or nail plate 20, adapted to fit 15 into the heel-portion of the shoe and to extend entirely over the heel seat thereof, the face thereof being formed to correspond to the usual formation of the interior of the shoe. A plurality of inwardly inclined 20 bosses 21 are formed on the opposite side of the plate 20 from its face side, and about the side edges thereof, at the inclinations and in the positions in which the several heel-attaching nails are preferably driven, 25 nail passages being formed through said bosses, which emerge in the face of the plate. A corresponding series of nail tubes 22 have screw threaded engagement with the ends of said bosses so that they extend in line 30 therewith, and therefore divergently from the plate 20, and a series of nail-guiding, spring fingers 23 are preferably clamped in position in said bosses by said tubes, see Fig. 3. The opposite ends of said tube 22 are 35 extended through a supporting plate 24, of similar shape to the nail plate 20, and are rigidly connected thereto by nuts 25 on said tubes, which clamp said plate against shoulders 26 on the tubes. In connecting the 40 plates 20 and 24, it is convenient first to screw the tubes 22 into the bosses 21, and then pass the opposite ends thereof from the bosses through the apertures in the plate 24. As the tubes extend divergently, it is 45 necessary to provide apertures of somewhat greater diameter than that of the tubes, to permit such simultaneous insertion. To make the construction rigid, bushings 29 are placed on the tubes after the latter have 50 been inserted and then are screwed into the apertures after which the nuts 25 are screwed onto the tubes. As shown in Fig. 4, the tube apertures in plate 24 are closely adjacent the side edge thereof, so that sufficient 55 space is provided in the middle portion of the plate to permit the convenient attachment of the post 17 thereto. The particular means shown consist of a pair of clips 27 which are secured to the middle portion of 60 the plate 24, about the ball 18, on the end of said post, recesses to receive which are formed in the adjacent sides thereof, so as to form a ball and socket joint connection between said post and the die block, which 65 permits universal tilting movement of said

plate with relation to said post 17, as well as relative rotary movement of the latter.

In using the device, the bracket and frame are locked in the position of Fig. 1, so that plate 20 is face uppermost, and will tilt forward to permit the ready application of the shoe. Then the shoe is placed on the last and the heel, to the base of which a coating of glue has been applied is placed in position on the heel-seat of the shoe. The last is then forced upwardly by the screw post 17, until the top of the heel is forced against the top-engaging block 14, both being tilted to the extent necessitated by the relative inclinations and positions of the top and base of the particular heel which is applied, as indicated by the dotted line position of Fig. 1. The heel will thus be firmly clamped against the heel-seat of the shoe in the position in which it is to be attached, slight irregularity in the heel seat being compensated for by the universal joint connection with the post. The bracket is then unlocked and turned the opposite end up, so that the shoe is held bottom down, as shown in Fig. 3. The usual attaching nails are then placed in the tubes, as also shown in Fig. 3, and are driven into the heel by the use of a hand driver 30, which is similar to, and is used like an ordinary nail set, the driver being placed on the heads of the nails in the tubes and struck with a hammer, so that they are driven successively.

On account of the inclined positions in which the nails are held, when first placed in the tubes, their points would tend to swing outward to such an extent that the nails would not be driven at the desired inward inclinations, unless properly directed. This difficulty is obviated by the 100 spring fingers 23, which hold the points of the nails in line with the center line of the tubes. The nails will thus be accurately guided, as they are driven, and will be driven in the position and at the inclination which is most advantageous. Many of the difficulties encountered in nailing by hand, in the ordinary way are thus avoided. Moreover, with the above described device 105 but little skill is required to enable the operator to drive the nails, while former methods require considerable skill and experience.

As soon as the nails have been driven, the shoe may be removed from the clamp, as the nails will hold the heel in position 110 while the glue dries. The heel is thus attached by both glue and nails in practically the same operation.

By having the whole clamp and support mounted to rotate about a horizontal axis, 115 the heel may be positioned with the shoe bottom side up, which is the most advantageous position in which this may be done, and may then be turned over and nailed while held bottom down. By providing the 120

pivotal connection between the clamp and its support, the clamp may be swung laterally, first to one side and then to the other, so that the workman may drive the nails 5 conveniently without changing his position in front of the jack. The whole operation may thus be performed much more rapidly than with previously employed hand methods, machines which drive the nails in a gang 10 being, so far as I am aware, but little used in attaching wood heels, by reason of their tendency to cause splitting of the heels.

I claim:—

1. A device for attaching wood heels comprising a clamp having a pair of clamp members consisting of a heel-part last and a top-engaging block, said last having a centrally disposed supporting means universally connected thereto and a series of 20 nail passages therethrough disposed about said supporting means at different inward inclinations.

2. A device for attaching wood heels comprising a clamp having a pair of clamp members consisting of a heel-part last and a top-engaging block each mounted to swing relatively to the other to conform to the angular relation of the base and top of the heel to be attached and said last having its 30 supporting means arranged to engage the middle portion thereof and having a series of nail-passages therethrough disposed about said supporting means.

3. A device for attaching wood heels comprising a frame having a pair of oppositely disposed arms, a pair of relatively adjustable clamp members mounted on said arms, respectively, and consisting of a heel-top engaging block and a post having a heel-part 40 last mounted on its end, said block and said last being relatively inclinable to conform to the angular relation of the base and top faces of the heel to be attached, and said last having a series of nail passages 45 therethrough disposed about the end of said post to permit the attaching nails to be driven through the last while the heel is clamped on the shoe held thereby.

4. A device for attaching wood heels, 50 comprising a clamp having oppositely disposed arms, a heel-top-engaging member supported on one of said arms, a post mounted on the opposite arm, and extending toward said member, and a heel-part last member mounted on the end of said post and having a series of nail passages therethrough disposed about the post to permit the attaching nails to be driven through 55 said passages while the heel is held clamped on the shoe by said members, and a pivotal support for said clamp arranged to permit the clamp to be swung laterally when held in upright position.

5. A device for attaching wood heels comprising a clamp having oppositely disposed 60

arms, a heel-top engaging block pivotally mounted on one of said arms, a post screw threaded in the other of said arms and extending toward said block, a heel-part last pivotally mounted on the end of said post 70 and having a series of nail-passages therethrough disposed about said end of the post, and means to support said clamp with either end uppermost.

6. A device for attaching wood heels comprising a support mounted to be moved about a horizontal axis, a clamp-frame mounted on said support to be swung laterally about an axis at right angles to said horizontal axis, said clamp having a pair 80 of oppositely disposed arms, a heel-top-engaging block pivotally mounted on one of said arms, and an adjustable post in the other arm and having a heel-part-last pivotally mounted on its end, said last having 85 a series of nail passages extending therethrough about the end of said post.

7. A device for attaching wood heels comprising a clamp having a pair of arms, a heel-top-engaging block on one of said arms, 90 a post on the other arm, a heel-part last mounted on the end of said post opposite its face side, and having a universal joint connection therewith and a series of nail passages therethrough disposed about said joint 95 connection, and means to adjust said block and said last relatively.

8. A device for attaching wood heels comprising a clamp having oppositely disposed arms, a heel-top engaging block pivotally 100 mounted on one of said arms, a post screw-threaded in the other of said arms and extending toward said block, a heel-part last pivotally mounted on the end of said post and having a series of nail-passages therethrough disposed about said end of the post, 105 a support for said clamp mounted to rotate about a horizontal axis which extends in a line which approximately intersects the center line of said post at right angles, and 110 means to lock said support in the two positions in which said post is held vertically.

9. In a device for attaching wood heels, a pair of clamping members for holding a heel pressed against the heel seat of a shoe, 115 one of said members comprising a plate-section having a centrally disposed support, and a series of apertures therethrough disposed about said support, a last-section adapted to fit into the heel portion of a 120 shoe, and having a corresponding series of apertures therethrough, and a series of nail guiding tubes rigidly connecting said sections and arranged in line with said apertures.

10. In a device for attaching wood heels, a pair of clamping members for holding a heel pressed against the heel seat of a shoe, 125 one of said members comprising a plate-section having a centrally disposed support, 130

and a series of apertures therethrough disposed about said support, a last-section adapted to fit into the heel portion of a shoe, and having a corresponding series of apertures therethrough inwardly disposed from the edge with relation to the apertures of said plate-section and a series of nail-guiding tubes rigidly connecting said sections

and extending convergently from said plate-section to said last-section in line with said apertures, respectively.

In testimony whereof I have signed my name to this specification.

FRED A. REARDON.

Witness:

L. H. HARRIMAN.
